UNITED STATES PATENT OFFICE.

EUGÈNE SCHNEIDER, OF LE CREUZOT, FRANCE.

AUTOMOBILE TORPEDO.

1,145,389.

Specification of Letters Patent.

Patented July 6, 1915.

Application filed July 30, 1914. Serial No. 854,033.

To all whom it may concern:

Be it known that I, EUGÈNE SCHNEIDER, of Le Creuzot, France, have invented a new and useful Improvement in or Relating to Automobile Torpedoes, which is fully set forth in the following specification.

This invention relates to automobile torpedoes of the kind in which the compressed air that drives the propelling engine is heated prior to its admission to the engine. For this purpose the apparatus for heating the compressed air has as is shown diagrammatically in Figure 1 of the accompanying drawing, comprised a combustion chamber 1 arranged between the compressed air reservoir 2 and the engine 3. The air coming from the reservoir 2 passes by pipe 9 to the inlet port of valve A' from which it leaves through conduit 10 and passes through pipe 6, forcing liquid hydrocarbon and water from the reservoirs 4 and 5 into the chamber 1 through the pipes 7 and 8 respectively. A conduit 11 supplies the combustion chamber 1 with compressed air. Upon these pipes, cocks are generally fitted and these cocks are opened before placing the torpedo in the launching tube. Now between the moment at which the said cocks are opened and the time of launching the torpedo which coincides with the actuation of the starting lever L and the opening of the air inlet, a considerable period of time elapses. During this interval of time, the pipes 7 and 8, the chamber 1 and the pipe which connects the latter with the engine become filled with combustible vapors. The result is that inopportune explosions often take place.

The chief object of the present invention is to avoid the possibility of explosions occurring when the ignition of the heating cartridge in the combustion chamber takes place, and to prevent faulty ignition and misfires which sometimes take place if the pressure in the said chamber varies suddenly.

The invention consists broadly in employing means for passing a supply of cold air through the combustion chamber and the pipe leading therefrom to the engine, before any admission of liquid hydrocarbon and water to the said chamber takes place.

For the purpose of the invention, the movements of the cock or cocks fitted to the liquid hydrocarbon and water pipes, are made dependent upon the position of mechanism which retards the actuation of the full

admission valve between the air reservoir and the engine. When this mechanism is constructed in accordance with my application for patent Serial Number 854,032 filed herewith, the retardation of the cock or cocks for the liquid hydrocarbon and the water is regulated at will and the return of the said mechanism to its initial position produced by the stopping mechanism then simultaneously produces the closing of the air inlet and the hydrocarbon. In other words, in this form of its application, the invention enables the following effects to be obtained: *a*, to produce running at a reduced speed prior to running at normal speed the said reduced speed running being with cold air in order to scavenge the combustion chamber and the engine and expel the explosive vapors that may be contained therein which might cause explosions at the moment of ignition of the cartridge; *b*, to render the heating apparatus operative only at the moment at which running at normal speed commences in order to avoid misfires due to sudden variations of pressure in the heater, and *c*, to prevent the flow of the liquid hydrocarbon and the water that would take place after the stopping of the torpedo, by the expansion of the air contained in the reservoir.

In order that the said invention may be clearly understood and readily carried into effect, the same will be described more fully with reference to the accompanying drawings, in which:

Fig. 1 is a diagrammatic illustration of a system for heating compressed air supplied to an automobile torpedo. Fig. 2 is a view in general sectional elevation showing my improvements and Fig. 3 a section on the line III—III of Fig. 2.

In these figures T designates a cock common to the pipes 7 and 8 for the admission of liquid hydrocarbon and water to the combustion chamber. In accordance with the invention, this cock is connected mechanically with an adjustable mechanism that retards the operation of the valve A—a for the full admission of air to the engine. The movement of the push rod b to lift the valve A—a is prevented, during a predetermined number of revolutions of the engine, by the striking of a member I against one element H of a clutch H—F, the other element F of which is actuated by gearing F—G from the engine. The push-rod b and the member

I are actuated by the usual balance lever B the movements of which are produced by the movements of the starting lever L.

K is the usual reduced admission valve 5 which is lifted as soon as the lever L is shifted into the position L' by the intermediary of a lever Q' and of a rod Q. The balance lever B actuates through a pin B² a clutch member C of a known stopping mechanism, 10 the companion member C' of which is adapted to be rotated by the motor and is subjected to the action of a spring R.

C² is an index finger. The balance lever B is connected by a rod B' with one arm of 15 starting lever L which controls the reduced admission valve K through a connection Q, Q'.

I designates a member which moves with the balance lever B and which is guided in 20 bearings J, J' rigid with casing A'. A spring r bearing at one end upon a ring M fixed in the member I and at the other end upon a fixed stop formed by the bearing J, constantly lends to return the member I to 25 the position represented in Fig. 2. In a casing E, which may be integral with casing A', a clutch member F is capable of rotating. The other clutch member H is provided with a tail piece carrying at its upper extremity an indicating hand H', which is 30 displaceable over a graduated dial H², by means of a stop not shown on ring H⁴. Around the rod carrying the clutch member H a torsion spring 2' is coiled; one end of 35 this spring is fixed to the member H and the other to a ring H⁴ pressed into the dial H² by a powerful spring H⁵. The member F is provided externally with teeth by means of 40 which it gears with a pinion F' keyed to a shaft G driven by the engine. A washer or collar M fixed to the member I and supporting the spring r of this member is provided with a pin N which actuates a bell crank lever O pivoted at a fixed point P and carrying an elongated hole O' (Fig. 3). A pin R 45 carried by an arm T' integral with the cock T engages in the hole O'.

The operation is as follows. At the moment at which the lever L of the starting 50 valve is brought rearward, to L', the engine starts at low speed with cold air, owing to the fact that the valve K and the member I are only lifted to the extent necessary for throwing-in the clutch H—F, this travel being insufficient to open the valve A—a and rotate the cock T. The cock T therefore remains closed so that the water and the liquid hydrocarbon do not reach the combustion chamber.

60 When at the end of a predetermined number of revolutions of the engine the member I engages in an orifice h in the clutch element H the clutch F—H is thrown out of operation and the full admission valve A—a 65 then opens fully and the engine commences

to run at its normal speed. At the same time the member I in rising opens the cock T by the intermediary of the collar M, the lever O and the arm T', and the water and the liquid hydrocarbon then reach the combustion chamber, to enable the heating of the air to commence. It will of course be understood that the ignition cartridge is so arranged that its firing does not take place until the end of the low speed running when 70 the valve A—a opens fully. With this object the firing may be controlled by a device connected with the push rod b or with the member I.

At the moment at which the torpedo 80 stops, the member I is returned by the balance lever B to its initial position; the spring r then causes the collar M to descend and close the cock T. Consequently the liquid hydrocarbon and the water cease to flow to 85 the combustion chamber. It is therefore easy by measuring the amount of liquid hydrocarbon and water remaining in their containers after the run of the torpedo to 90 exactly ascertain the quantity consumed 90 during the run.

What I claim and desire to secure by Letters Patent of the United States is:—

1. In an automobile torpedo, the combination of an engine, a source of compressed 95 air, and a source of liquid fuel, valve controlled conduits connecting the engine with said sources, means for opening said air valve to start and scavenge the engine and means controlled by a predetermined number of revolutions of the engine for timing the opening of the fuel valve after the engine is scavenged.

2. In an automobile torpedo, the combination of an engine, a preheating chamber 10 therefor provided with a source of vaporizable liquid and a compressed air supply; valve means for controlling said fluid supplies to said engine through said chamber comprising a reduced air admission valve, a 11 full air admission valve and a valve controlling said liquid supply; means for operating said valves including a push rod having means controlled by a predetermined number of revolutions of the engine for retarding action of said rod on the full admission valve, and connections between said rod and said liquid admission valve.

3. In an automobile torpedo, the combination of an engine, a preheating chamber 12 therefor provided with a source of vaporizable liquid and a compressed air supply, valve means for controlling the supply of fuel and air to said engine through said chamber comprising a reduced air admission valve, a full air admission valve and a valve controlling the supply of said liquid, means for operating said valves and means for timing the action of said operating means on the two last named valves to open 13

the same after opening the reduced air admission valve for the purpose of scavenging the combustion chamber and engine.

4. In an automobile torpedo, the combination of an engine, a source of compressed air and a source of vaporizable liquid therefor; valve means controlling said fluid supplies, comprising a reduced air admission valve, a full air admission valve, and a 10 valve controlling the said liquid supply; means for operating said valves and means for timing the action of said operating

means to open the two last named valves after opening the reduced air admission valve for the purpose of scavenging said 15 engine.

In testimony whereof I have signed this specification in the presence of two subscribing witnesses.

EUGÉNE SCHNEIDER.
